(57) **CLAIM**

The ornamental design for a dental X-ray sensor cover, as shown and described.

DESCRIPTION

FIG. 1 is a front top isometric prospective view of the present design for a dental X-ray sensor cover;

FIG. 2 is a front back view of the dental X-ray sensor cover of the design of FIG. 1;

FIG. 3 is a cross-sectional view of the dental X-ray sensor cover of the design of FIG. 1 taken along the 3-3 line of FIG. 2;

FIG. 4 is a right bottom view of the dental X-ray sensor cover of the design of FIG. 1; and,

FIG. 5 is a perspective view showing the dental X-ray sensor cover in a state of use enclosing a dental X-ray sensor. The even length broken lines illustrate environment and form no part of the claimed design. The dot-dash broken lines illustrate the direction of the cross-sectional view and form no part of the claimed design.
